CLAIM

The ornamental design for an end cap for a luminaire, as shown and described.

DESCRIPTION

FIG. 1 is a perspective view of a new design for an end cap for a luminaire as seen from the top, rear, left side;

FIG. 2 is a perspective view thereof, as seen from the top, front, left side;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines illustrate portions of the end cap for a luminaire and form no part of the claimed design.
